UNITED STATES PATENT OFFICE.

CARL H. HARTMAN, OF TOLEDO, OHIO, ASSIGNOR TO THE VALVE BAG COMPANY OF AMERICA, OF TOLEDO, OHIO, A CORPORATION OF OHIO.

BOTTOM CLOSURE FOR PAPER-BAG MACHINES.

Application filed January 23, 1924. Serial No. 387,990.

To all whom it may concern:

Be it known that I, CARL H. HARTMAN, a citizen of the United States, and a resident of Toledo, in the county of Lucas and State of Ohio, have invented a new and useful Bottom Closure for Paper-Bag Machines, which invention is fully set forth in the following specification.

My invention relates to paper-bag machines, and more particularly to bottom folders for such machines.

My invention has for its object to provide means for folding the bottoms of bags in a simple manner which will effect such folding rapidly and with certainty.

One embodiment of my invention is shown in the accompanying drawings, in which Figure 1 is a section through the bottom-folding apparatus along the line 1-1 of Fig. 4, with many of the parts indicated diagrammatically; Figs. 2 and 3 are views of the bottom-folding means in successive positions; Fig. 4 is a partial plan view; Fig. 5 is a section on the line 5-5 of Fig. 4, and Figs. 6 and 7 are views of the folding segments. Fig. 8 is a diagrammatic view of a position between those of Figs. 2 and 3.

In the type of paper bag machine to which this invention relates, paper strips are fed continuously into the machine and folded into tubular form. Successive lengths are cut from the tube and successive sections are opened up at one end, creased and folded to form bottoms, thus completing the bags.

The portion of the apparatus to which this invention relates is the device for folding the flaps of the bottom to complete the bag-forming operation. A creasing roll 10 is shown diagrammatically with a bag 11 indicated in position thereagainst. A co-operating creasing roll 12 carries creasing blades 13 and 14. These blades co-operate with grooves in the roll 10 to form creases in the bag bottom along the lines at which the forward flap 15 and the rear flap 16 of the bottom are folded. The successive bags are held in position against the roll 10 by tapes 17. These creasing rolls operate in a well-known manner and form no part of my invention.

A finger 18 is pivoted at 19 to an arm 20 of a rock shaft 21. The rock shaft 21 is operated by an arm 22, which is connected

to a member 23 by pivot 24. The member 23 has its free end forked at 25 and the two arms of the fork pass upon opposite sides of the shaft 26. A roller 27 mounted on the member 23 operates within a cam groove 28 in disc 29, which is operated in unison with the creasing roll 12 so that the finger 18 is oscillated for each rotation of the creasing roll. A rear extension of the finger 18 carries a cam roller 30, which is normally urged by a spring 31 into contact with a cam 32. By this means the finger 18 is rocked in the desired manner to fold the rearward flap towards the forward flap, as indicated by the positions shown in Figs. 1 and 2.

A shaft 40 is mounted beside the creasing roller 10 and carries a gear 41, in engagement with a gear moving in unison with the roller 10. The shaft 40 carries two segments 42, and the parts are so proportioned that these segments 42 have a surface speed substantially equal to that of the roller 10 and are so located that the following portions 43 of the segments contact the forward flap 15 and roll it down against the roller 10, as clearly indicated in Fig. 2. Two sleeves 44 surround the shaft 40, each sleeve carrying a segment 45 adjacent a segment 42. The sleeves are driven at such a speed that they will rotate a multiple of the times which the shaft 40 rotates. I prefer the proportion to be three to one. The leading corner 46 of each segment 45 is beveled slightly, so that it will properly fold the following flap 16, as will be seen from Fig. 8. The segments 45 rotate with such speed that the following ends 47 press the flap 16 into position against the flap 15. A shaft 48 carries a gear 49, meshing with a gear on the end of creasing roll 10, and two sprocket chains 50 are driven by sprocket wheels 51 on shaft 48 and drive sprocket wheels 52 on sleeves 44.

Pulleys 53 are mounted on sleeves 44, and drive the tapes 17. A shaft 54 carries arms 55, which carry rollers 56, which hold the tapes 17 against the surface of roller 10. Tapes 58 passing around roller 10 and over roller 59 strip the bags from the creasing roller. Tapes 60 pass over roller 61, in contact with roller 59, between the final delivering rollers 62 and 63 and over the guide roller 64. Shaft 54 carries arms 65 which

support rollers 66 in position to receive the tapes 60 to carry the bag upward as it is delivered from the creasing roller.

The operation of the device will be apparent from the description of its construction, but may be briefly summarized as follows:

- As successive bag-bottoms pass between the creasing rollers 10 and 12, creases are formed along the lines where flaps 15 and 16 are to be folded. The finger 18 moves the flap 16 forward more rapidly than the bag is moving so that, by the time the parts reach the position shown in Fig. 2, the flap 16 will project into the space between segments 42 and 45. In the meantime, the forward flap 15 has encountered segment 42 and will be folded down so that the flap 16 may be folded over it. The leading corner 20 of the rapidly moving segment 45 then encounters the flap 16 and completes the folding operation, and the succeeding portions of the surfaces of the segments hold the flap 16 down in its folded position until 25 it is delivered between the tapes 58 and 60, which carry off and deliver it from the machine. The tapes 17 contact the sides of the bag beyond the bottom flaps, and the crease 67, along which the flap 16 is folded, 30 is allowed to drop away from the creasing roll a slight distance, as shown. When the finger 18 pushes the flap 16 forward, the entire bending does not take place at the crease 67, but the paper adjacent that crease is bent to some extent, which causes the crease to move away from the roller. There is some variation in the register of the bags with the segments and some variation in the distance crease 67 drops away from the 35 creasing roller, but the bevel 46 is sufficient to insure that the segment will not enter behind crease 67, but will contact the outer side of the flap and bring it into proper position.
- 40 This arrangement allows extremely rapid operation without danger of breaking the flaps or scattering the paste, and so endangering the sealing operation.

It has been previously proposed to fold 45 the flaps by rotary segments rotated at the same speed. With that arrangement, the forward flap is held down for a very short time and the rear flap has to be moved forward with such speed that there is danger 50 of scattering the paste and even breaking the paper. In the improved construction shown herein, the segment contacting the leading flap moves at the same speed as the creasing roller and, therefore, holds this 55 forward flap down for a considerable time and gives opportunity for a more gradual movement of the rear flap into position against the forward flap.

The means for operating the finger 18 disclosed herein gives satisfactory results, but

may be varied as desired without affecting the operation of the segments, and any other suitable means may be substituted for folding the rear flap into position where it will be operated upon the folding segments. 70

Various changes in the shape and operation of the parts may be made within the scope of the appended claims without departing from the spirit of the invention. 75

What I claim is:—

1. In a paper bag machine, bottom-closing means comprising separate members for folding the two flaps, a shaft upon which said members are mounted and driving connections for rotating said members about said shaft, said connections being arranged to rotate the rear valve-folding members more rapidly than the front valve-folding members. 80

2. In a paper bag machine, bottom-closing means comprising segments for folding the two flaps, a shaft upon which said segments are mounted, means for moving bag blanks past said segments, means for rotating the front flap-folding segment at substantially the surface speed of the bag blank, and means for rotating the rear flap-folding segment a multiple of the number of times that the front flap folder is rotated. 90

3. In a paper-bag machine, bottom-closing means comprising a creasing roll, a shaft adjacent the creasing roll and carrying a segment adapted to contact the forward flap of a bag on the roll, means to drive the segment at a surface speed substantially equal to that of the roll, a sleeve surrounding the shaft and carrying a segment adapted to contact the rear flap and means to rotate the sleeve at a multiple of the speed of the front flap folder. 95

4. In a paper-bag machine, bottom-closing means comprising a creasing roll, a shaft adjacent the creasing roll and carrying a segment adapted to contact the forward flap of a bag on the roll and means to drive the shaft so that the segment will have a surface speed substantially equal to that of the roll, sleeves surrounding the shaft on each side of the segment, segments on the sleeves adapted to contact the rear flap, means for rotating the sleeves more rapidly than the shaft, tapes adapted to hold the bags against the roll, and pulleys on the sleeves of such size as to receive and drive the tapes at a speed substantially equal to that of the roll. 110

5. A paper bag machine comprising a creasing roll and a rear flap-folding segment having a surface speed greater than that of the roll, the leading corner of the segment being beveled to wedge the flap towards the roll. 115

In testimony whereof I have hereunto signed my name to this specification.

CARL H. HARTMAN.
